PRESSING MACHINE

Ernest Davis, Syracuse, N. Y., assignor to The Prosperity Company Inc., Syracuse, N. Y., a corporation of New York

Application May 12, 1928, Serial No. 277,109

9 Claims. (Cl. 68—9)

This invention relates to pressing machines, particularly garment or cloth pressing machines where steam is blown into the garment or cloth to moisten it preliminary to a pressing and drying operation, and air is blown into the goods or garment to condense the steam to form moisture and after the pressing operation to cool the garment; and it consists in a particularly simple and efficient means for actuating and controlling the actuation of the movable element of the pressing machine and the flow of air and steam into the garment or goods being operated upon.

The invention consists in the novel features, and in the combinations and constructions hereinafter set forth and claimed.

In describing this invention, reference is had to the accompanying drawings in which like characters designate corresponding parts in all the views.

20 Figure 1 is a side elevation, partly broken away, of this pressing machine.

Figure 2 is a sectional view, partly diagrammatic, of the actuating and control mechanism for the movable pressing element.

25 Figure 3 is a fragmentary elevation, partly in section, of the lower pressing element illustrating the means for controlling the flow of two fluids as steam and air to the work between the pressing elements.

30 Figure 4 is a diagrammatic fragmentary plan view illustrating the relative position of the manu-
als of the machine.

Figure 5 is a sectional view through the head of the machine.

35 The machine, here illustrated, is of the conventional type including cooperating pressing elements, one of which is movable toward and from the other, the movable element being here shown as a head 1 movable toward and from the buck 2, the buck being mounted on a bracket or goose neck 3, which is mounted on a bench or table 4 supported by the usual frame 5.

The head 1 is usually carried by a yoke lever 6 pivoted between its ends at 7 to a standard 8 rising from the frame.

40 As seen in Figure 5, the head 1 is formed with an internal chamber 9 for receiving a heating medium as steam and also with a lengthwise channel 10 and with a by-pass 11 connecting the steam chamber 9 and the channel 10, this passage being controlled by a valve 12 operated by a handle 13.

The side 14 of the channel on the pressing face of the head 1 is formed with perforations or jet 45 openings for permitting the outlet of steam when

the valve 12 is opened and also the pressing face of the head is covered by a layer of wire mesh 15, this being normally spaced apart from the pressing face in order to permit the steam to be distributed over the face of the head. The wire 5 mesh also performs other functions such as preventing the formation of a shiny finish on the goods, and also because of its thickness permits the moisture to evaporate out of the garment when under pressure.

10 This invention comprises motor means, connections between the motor means and the movable element or head 1 and operator-operated means for controlling the operation of the motor means to actuate the head into a position close 15 to the buck or other element and preferably into light pressure coaction with the other element or buck, and also additional operator-operated means for controlling the motor means to actuate the head into heavy pressure coaction with the 20 buck, the operator-operated means being operable successively to effect a two step operation of the machine. By the two-step operation, the motor means is operated first to preliminarily bring the movable element toward and preferably 25 into light pressure coaction with the buck and second to bring the movable element into full pressure position. The two operator-operated means also are operable simultaneously to effect a one step operation to bring the head into full 30 pressure position from wide open position. One of the objects of the two step operation is to perform a moistening operation while under light pressure before heavy pressure is applied to shape and dry the goods or garment.

35 The motor means here illustrated comprises two motor units, both of which coact to apply heavy pressure and one of which acts for the most part to preliminarily close the press. The motor means here shown comprises two cylinders 40 16, 17 and pistons 18, 19 movable in their respective cylinder. A separate motion transmitting means is provided between each of the pistons and the head 1 or the yoke lever 6, whereby nearly full throw of the piston 18 brings the head 45 1 nearly down on the buck 2 or under light pressure coaction with the buck 2 and nearly full throw of the piston 19 through lever mechanism effects a final heavy pressure, full movement of both pistons being required to bring about heavy 50 pressure.

In the illustrated embodiment, the cylinder 16 is pivoted at its lower end 20 to the frame 5 and the piston moves upwardly therein under the pressure of a motive fluid, as air, and its rod 21 55

is pivoted at 22 to the rear arm of the yoke lever 6. The cylinder 16 is provided with a packing 16^a in the nature of a valve packing, against which the piston 18 seats when it reaches the end of its out stroke, this packing preventing the leakage of air along the cylinder walls.

The motion transmitting mechanism between the piston 19 and the head 1 or the rear arm of the yoke lever 6 includes the piston rod 23, a combined lever and pull link 24 to which the lower end of the piston rod 23 is pivoted at 25, toggle links 26 and 27 pivoted together at 28 and pivoted respectively at 29 to the frame and at 30 to the rear end of the yoke lever, the link 24 being pivoted at 31 to one of the toggle links. The link 24 fulcrums with a sliding action on the frame at 32. The link 24 is guided in its movement by a cam slot 33 formed in a bracket 35 fixed to the frame and having an upper portion inclined slightly out of the horizontal and a rearward and downward portion inclined out of the vertical. The link 24 has a follower movable in the slot.

While the head is being closed principally under the action of the piston 18 in the cylinder 16, the follower is traveling along the upper portion of the slot 33 which is inclined out of the horizontal and hence very little movement of the piston 19 takes place. While heavy pressure is being applied primarily by piston 19 in the cylinder 17, the follower is moving in the lower portion of the slot which is inclined out of the vertical. The incline of the upper portion of the slot out of the horizontal is such that it does not prevent the actuation of the piston 19 when the motive fluid is permitted to enter simultaneously into both cylinders or into the cylinder 17 before it enters the cylinder 16. The degree of incline of the upper portion of the slot 33 is a matter of selection and where, as particularly described herein, it is desired that the high power motor 17 shall participate in the initial closing movement of the head 1 by depressing the buttons 51 and 63, the incline must be at least sufficient to obtain this result. The effect of the motor 16 in impelling the cam roller to the right as shown in Figure 1, has some bearing on the amount of incline required. The pistons are single acting. The press is opened when the motive fluid or air is permitted to exhaust from the cylinders by countersprings 35, 36. The cylinder 17 is pivoted at 37 at its upper end to the frame and the piston moves downwardly therein on its power stroke.

55 The operator-operated means for controlling the flow of motive fluid, as air, to the cylinder 16 as here shown comprises a pedal 38 pivoted at 39 to the base of the frame and connected to a rod 40, which through a spring 41 acts on the lever 42 which effects the closing of a normally open exhaust valve 43 and the opening of a normally closed intake valve 44 in a valve casing 45, the valves being connected so that they act as a unit by a stem 46. The intake valve 44 is spring 65 pressed so that it is normally held in its closed position and the exhaust valve is normally held in its open position.

The valve casing 45 is connected by a pipe 47 to a port 48 in the head of the cylinder 16, this port opening into the cylinder 16. The intake end of the valve casing 45 is connected by a pipe 49 to a feed pipe 50 which is connected to a suitable source of compressed air.

Obviously upon depression of the pedal 38, the 75 exhaust valve 43 will be closed and the intake valve

44 opened, permitting air to pass through the pipe 47 into the cylinder 16. When the valves are in their normal position or are returned to their normal position, the air is free to exhaust from the cylinder 16 back through the pipe 47, 5 valve casing 45 and out through an exhaust passage 43^a.

The flow of air to the cylinder 17 is controlled by a manual, as a push button 51 which acts on a lever 52 which in turn acts on a lever 53 coacting with the stem 54 of a normally open exhaust valve 55 which is connected by a stem 56 to a normally closed spring pressed intake valve 57, the valves being located in the casing 58. The casing 58 is connected by a pipe 59 to a coupling 15 60 communicating with a port 61 in the head of the cylinder 17, this port opening into the upper end of the cylinder 17. The intake end of the valve casing 58 is connected by a pipe 62 to the feed pipe 50.

20 Obviously, upon depression of the push button 51 air will pass from the feed pipe 59 through a valve casing 58 and pipe 59 into the cylinder 17 to actuate the piston therein. When the valves are returned to their normal position, the air 25 is free to exhaust out of the cylinder 17 back through pipe 59, valve casing 58 and exhaust port 55^a controlled by the exhaust valve 55.

Preferably, both hands of the operator are occupied when the press is being closed under final 30 heavy pressure in order to prevent injury to the operator and therefore two manuals are provided requiring that both hands of the operator be so occupied. These push buttons are operable independently of the operator actuated 35 control member 43, 45.

The other manual consists of a push button 63 acting on the lever 64 which in turn acts on a lever 65 which coacts with the stem 66 of a normally open exhaust valve 67 in the valve 40 casing 68, this valve casing being connected by a pipe 69 to the coupling so that if the push button 63 is not depressed when the push button 51 is depressed, the air will exhaust out through the valve casing 68 instead of passing into the 45 cylinder 17.

Means is provided for holding the valves, operated by manuals 51, 63, in their operated position. The means here shown are pressure operated and include diaphragm chambers 70 and 71 having diaphragms 72 and 73 therein coacting with sliding stems 74 and 75 which act upon the levers 63 and 65 respectively.

The pressure sides of the diaphragm chambers 70 and 71 are connected by pipes 76 and 77 to a 55 pipe 78 which communicates with a casing 79 having a port 80 opening into the cylinder 17 and arranged to be uncovered by the piston when the piston is well on its out stroke, so that the back pressure from the cylinder passes back 60 through the pipes 78, 76 to the diaphragm chambers 70 and 71 and acts on the diaphragms therein to hold the valves in the casings 58 and 68 in their operated position.

The pressure is released in the diaphragm 65 chambers to permit these valves to move to their normal position, in which the exhaust valves are open, by a normally closed spring pressed exhaust valve 81 in a valve casing 82 which is connected by a pipe 83 to the pipe 76. This release 70 valve 81 is operated by a lever 84. Obviously upon the operation of the lever 84, the exhaust valve 81 will be opened permitting the air to exhaust from the diaphragm chambers and hence 75 permitting the exhaust valve 55 to open.

and the intake valve 57 to close, so that air can exhaust from the cylinder 17, through the pipes 59, 69, valve casings 58 and 68 and out through exhaust passages 55^a and 67^a.

5 Thus when the head is under final pressure, the operation of the trip lever 84 will release the head of the heavy pressure although the head will be held under light pressure by the piston 18 in the cylinder 16, if the operator continues 10 to hold his foot on the pedal 38.

To lock the press closed without the necessity of holding down the pedal 38, means is provided for locking the intake valve 44 open and the exhaust valve 43 closed, these being the valves 15 operated by the pedal 38. This holding means includes a diaphragm chamber 85 having a diaphragm 86 therein acting on a sliding stem 87 which in turn acts on the lever 42. The pressure side of this diaphragm chamber 85 is connected by pipes 88 and 89, valve casing 90 and pipe 91 to the pipe 49 which is connected to the feed pipe 50.

20 The flow of air through the valve casing 90 is controlled by a normally closed spring pressed intake valve 92 therein, a normally open exhaust valve 93 connected by a stem 94 with the valve 92, and these valves are operated by a manual or lever 95 coacting with the stem 96 of the exhaust valve 93. Upon depression of the lever 30 95 the exhaust valve 93 will be closed and the intake valve 92 opened permitting air to flow from the main line through the valve casing 90, pipes 89 and 88 to the diaphragm chamber 85. This mechanism provides means which are operable at will for locking the first control member 43, 45 in its operated position.

35 The valves 92 and 93 are locked in their operated position by a diaphragm chamber 97 having a diaphragm 98 therein coacting with a sliding stem 99 which acts on the lever 95. The pressure side of the diaphragm chamber is connected by duct 100 to the interior of the casing 90 so that when the lever 95 is depressed and hence the exhaust valve 93 closed and the intake 45 92 opened, the air will enter the diaphragm chamber and hold the lever 95 in its operated position.

To open the press or to release either the pressure in the cylinder 16 or release the pressure 50 simultaneously in both cylinders 16 and 17, additional means is provided for releasing the pressure in the diaphragm chambers 70 and 71 and also in the chambers 85 and 97. This means comprises normally closed exhaust valves 101 and 102 located 55 in chambers 103 and 104 of a valve casing 105. The chamber 103 is connected by a pipe 106 to any one of the pipes 76, 77 or 78, it being here shown as connected to the pipe 77; and the chamber 104 is connected by a pipe 107 to the pipes 88 and 89.

60 The valve 101 is operated by a lever 108 and the valve 102 is operated by a lever 109 which thrusts at 110 against the lever 108 so that the operation of the lever 109 also actuates the lever 108.

To release the pressure in the diaphragm chambers 70 and 71 and hence release the pressure in the cylinder 17, the lever 108 may be operated, and to release the pressure in all the diaphragm chambers to effect a complete opening 70 of the press, the lever 109 is operated. The lever 109 contacts with the lever 108 at 110 so that operation of the lever 109 will also operate the lever 108 and open both of the exhaust 75 valves 101 and 102.

The lever 108 performs the same function as the lever 84. The levers 108 and 109 are usually a remote control. An operator usually operates two machines designated generally A and B. The remote control for machine A is located on machine B and the remote control for machine B is located on machine A so that an operator after closing the press, as machine A, can entirely open up or partly open up machine B from machine A so that it will be open by the time he reaches 10 machine B.

In order that both cylinders 16 and 17 and the pistons therein may be utilized to produce final heavy pressure when the push buttons 51, 63 are operated to close the press with a one step 15 operation, the cylinders are connected together so that they act as a single motor, by a pipe 17^a connecting the intake end of the cylinder 17 to the intake end of the cylinder 16 or to the pipe 47. This pipe 17^a has a spring pressed check valve 20 17^b therein arranged to prevent the flow of air into the cylinder 17 from the pipe 47 or the cylinder 16 but permits the flow of air from the cylinder 16 to the pipe 47 when sufficient pressure is developed in the cylinder 17 to overcome the 25 spring of the check valve. When the air passes through the pipe 17^a from the cylinder 17, it will pass out through the exhaust valve 43 unless this valve 43 is closed and the intake valve 44 opened by operating the pedal 38 or the manual lever 95. 30

The incline of the upper portion of the cam slot 33 is such that when the push buttons 51, 63 are operated, the piston 19 can travel far enough to close the head preliminarily or lightly down on the buck with little or no pressure, the 35 follower on the combined push rod and lever 24 moving along the upper portion of the cam slot 33 to an angle of the cam slot. At this point in the operation, the check valve 17^b opens, as it requires less pressure to open the check valve 40 than to actuate the piston 19 to apply heavy pressure, the check valve being opened, the air will leak out from the cylinder 17 through the pipe 17^a, pipe 47, valve casing 45 and past the open exhaust valve 43 unless the exhaust valve 45 43 is closed and the intake valve 44 opened by the depression of the pedal 38 or the manual lever 95. Hence both cylinders operate to apply final heavy pressure.

During the closing of the press, either by first 50 depressing the pedal 38 or the push buttons 51, 63, the piston 19 travels nearly half the length of the cylinder 17 before the head comes down onto the buck.

Steam and comparatively cold air are blown 55 into the garment to generate moisture in the garment which is distributed equally through the garment. Thereafter the garment is dried by heat and pressure, and thereafter, if desired, relatively cold air may be blown into the garment to cool it.

The means for blowing air and steam will now be described, which means is associated with the buck 2 although the head also has means controlled by the lever 13 for blowing steam into 60 the garment form the top thereof.

As seen in Figure 3, the buck 2 is formed hollow with a chamber 111 for receiving steam and with a lengthwise channel 112 having perforations or jet openings 113 opening through the 70 pressing face of the buck. The buck is overlaid with a spring padding 114 and layers of padding 115 and a wrapper 116. The arrangement of the chamber 111 and channel 112 is substantially like chamber 9 and channel 10 of the head 1. 75

The buck is also formed with an inlet duct 117 for the steam and an inlet duct 118 for the air and these ducts register respectively with passages 119 and 120 formed in the goose neck or bracket 3. The buck is also formed with an outlet duct 121 leading from its steam chamber 111 which registers with a passage 122. The passages 119 and 122 communicate with the interior of a valve casing 123 which controls the flow of steam from chamber 111 through the passages 121, 122, valve casing 123, passages 119 and 117 to the channel 112. The air passage 120 communicates with a pipe 124 which is connected through valve controlled means to the feed pipe 50.

The steam valve 123 is preferably operated by compressed air. The means for operating the steam valve comprises a diaphragm chamber 125 having a pair of spaced apart diaphragms 126 and 127 therein. The diaphragm 126 acts on the stem 128 of the valve. The space between the diaphragms is connected to a pipe 129 which is also connected to a valve casing 130 having a normally open exhaust valve 131 therein and a normally closed spring pressed intake valve 132, these valves being connected by a stem 133 whereby they act as a unit.

The intake end of the valve casing 130 is connected by a pipe 134 to a pipe 135 which is connected to a branch 136 of the main feed line 50 for the air.

The valves 131 and 132 are operated by a pedal 137 pivoted at 138 to the base of the machine and connected by a rod 139 to a lever 140 which coacts with the stem 141 of the exhaust valve. The motion of the link 139 is yieldingly transmitted to the lever 140 through a spring 142.

The valve 131 controls an exhaust passage 131^a. Upon depression of the pedal 137, the exhaust valve 131 will be closed and the intake valve 132 opened, so that air passes through the valve casing 130 and pipe 129 into the space between the diaphragms 126, 127 and actuates the steam valve 123 to open it to permit steam to pass into the channel 112, through the jet openings 113, through the padding and wrapper and into the goods or work on the buck.

The pedal 137 is returned to its normal position by a spring 143. When the pedal 137 is released, the air is free to exhaust from the space between the diaphragm chambers 126 and 127 back through the pipe 129, valve casing 130 out through the exhaust passage 131^a and thus permit the steam valve 123 to close.

The steam valve 123 may be manually operated as by a manual 144 coacting with the stem 145 of an exhaust valve 146 in a valve casing 147, the exhaust valve being connected by a stem 149 to a normally closed spring pressed intake valve 150. The exhaust valve controls an exhaust passage 148^a. The intake end of the casing is connected by a pipe 151 to the air pipe 135.

When the lever 144 is moved downwardly, Figure 3, or to the left, Figure 4, the exhaust valve 146 will be closed, the intake valve 149 opened, so that air passes through the valve casing 147 and pipe 151 to the diaphragm chamber 125 below the diaphragm 127, thus actuating the stem 128 of the steam valve to open it.

The blowing of air is also controlled by the lever 144, this lever having a movement from neutral in opposite directions so that air and steam can be alternately blown by moving the

lever in opposite directions, or the air and steam may be blown at the same time by depressing the pedal 37 and moving the lever 144 upwardly, Figure 3, or to the left, Figure 4.

The lever 144 also coacts with a stem 152 and a normally open exhaust valve 153 coupled by a stem 154 to a normally closed spring pressed intake valve 155, these valves being located in a casing 156.

The intake end of the valve casing 156 is connected to the air pipe 136. The exhaust valve 153 does not function as an exhaust valve but its primary function is to act as a packing when the intake valve 155 is open. This construction avoids the use of a packing that will become leaky and also permits the use of one kind of valve throughout the machine. In other words, a valve arrangement as 153 is used instead of a packing that would become loose.

Upon movement of the lever 144 upwardly, Figure 3, or to the left, Figure 4, air will pass through the valve casing 156, pipe 124, passages 120 and 118 into the channel 112 of the buck and out through the perforations 113 and the padding and wrapper of the buck and carry the steam therefrom into the garment and also as the air is comparatively cold, will condense the steam in the garment and moisten the garment. The air will also condense the steam in the garment regardless of whether the garment is steamed from the head or from the buck.

In the operation of the complete machine, the operator after arranging the work on the buck depresses the pedal 38, permitting air to enter cylinder 16 and actuate the piston 18 therein thus bringing the head 1 down close to and preferably under light pressure on the buck. He then operates the lever 144 to the right, Figure 4 or downwardly, Figure 3, to operate the steam valve to permit steam to be blown into the garment. He may also operate the lever 13 to permit steam to be blown into the garment from the head 1. He then operates the lever 144, to the left, Figure 4 or downwardly Figure 3, thus discontinuing the flow of steam and permitting the cold air to blow through the padding and the garment to condense the steam therein and moisten the garment and to blow the garment.

The push buttons 51, 63 are then depressed to permit air to enter the cylinder 17 and actuate the piston 19 therein to the end of its power stroke. The movement of the head by the piston 18 moves the piston 19 more or less, depending on the inclination and form of the upper portion of the cam slot 33, during the closing of the press and during such movement the follower is traveling along the upper portion of the cam slot 33 which portion is inclined slightly out of horizontal. However, the piston 19 moves through the greater part of its stroke when applying heavy pressure through the toggle links 26, 27 and link 24. The machine may then be locked under pressure when the garment is drying by depressing the lever 95 thus permitting air to enter the diaphragm chambers 85 and 97.

The machine may be completely closed in a one step operation from wide open position by depressing the pedal 38 and push buttons 51, 63 simultaneously.

The machine is completely released so as to open wide by operating the lever 109 of the remote control mechanism or it may be partly released to remain under light pressure by either operating the lever 108 of the remote control mechanism or the lever 84.

Steam may be blown regardless of whether the machine is open or under light pressure or under heavy pressure by depressing the pedal 137 or steam or air may also be blown at any time by operating the lever 144; both steam and air can be blown simultaneously by depressing the pedal 137 and operating the lever 144 downwardly, Figure 3, or to the right, Figure 4.

What I claim is:

- 10 1. In a pressing machine, cooperating pressing elements, one of which is movable toward and from the other, two cylinders and pistons therein, and motion transmitting means individual to each piston between the pistons and the movable element, operator-operated means individual to each cylinder for controlling the flow of motive fluid to each cylinder independently, and means connecting the cylinders and permitting fluid flow from the second cylinder to the first cylinder only, whereby upon operation of the pistons successively the press is closed with a two-step operation and upon the operation of the second piston the press is closed with a one-step operation.
- 15 2. In a pressing machine, cooperating pressing elements, one of which is movable toward and from the other, two cylinders and pistons therein, motion transmitting means individual to each piston between the pistons and the movable element, operator-operated valve means individual to each cylinder for controlling the flow of motive fluid to each cylinder independently of the other cylinder, means connecting the cylinders and permitting fluid flow from the second cylinder to the first cylinder only whereby upon the operation of the second piston, the press is closed by a one-step operation, the operator-operated valve means for the second cylinder including two manuals and means whereby both manuals must be operated to effect the flow of motive fluid to the second cylinder.
- 20 3. In a pressing machine, cooperating pressing elements, one of which is movable toward and from the other, two cylinders and pistons therein, and motion transmitting means individual to each piston between the pistons and the movable element, operator-operated means individual to each cylinder for controlling the flow of motive fluid to each cylinder independently, means connecting the cylinders and permitting fluid flow from the second cylinder to the first cylinder only whereby upon the operation of the second piston successively, the press is closed with a two-step operation, and upon operation of the second piston the press is closed with a one-step operation, and operator-operated means for locking the movable element from opening movement when the press is in preliminarily closed position.
- 25 4. In a pressing machine, cooperating pressing elements, one of which is movable toward and from the other, two cylinders and pistons therein, and motion transmitting means individual to each piston between the pistons and the movable element, operator-operated means individual to each cylinder for controlling the flow of motive fluid to each cylinder independently, a fluid connection between the cylinders, and valve means in the connection permitting fluid flow from the second cylinder to the first cylinder only whereby upon operation of the second piston successively the press is closed with a two-step operation and upon the operation of the second piston the press is closed with a one-step operation.

5. In a pressing machine, cooperating pressing elements, one of which is movable toward and from the other, a first cylinder having a piston therein, motion transmitting means between the first piston and the movable element, a second cylinder having a piston therein, a toggle operatively connected with the movable element, means operatively connecting the second piston with the toggle so that a large extent of movement of the piston moves the toggle a relatively short distance during its final pressure movement, operator-operated means individual to each cylinder for controlling the flow of motive fluid to each cylinder independently, and means connecting the cylinders and permitting fluid flow from the second cylinder to the first cylinder only whereby upon operation of the pistons successively the press is closed with a two-step operation and upon the operation of the second piston the press is closed with a one-step operation.

6. In a pressing machine, cooperating pressing elements, one of which is movable toward and from the other, a first cylinder having a piston therein, motion transmitting means between the first piston and the movable element, a second cylinder having a piston therein, a toggle operatively connected with the movable element, a pull link connected to one of the toggle links, cam means carried by the frame and pull link to guide the latter, the pull link being operatively connected with the second piston through the cam means to permit a large extent of movement of the toggle initially with a small extent of movement of the piston and a small final extent of movement of the toggle with a large final movement of the second piston, operator-operated means individual to each cylinder for controlling the flow of motive fluid to each cylinder independently, and means connecting the cylinders and permitting fluid flow from the second cylinder to the first cylinder only whereby upon operation of the pistons successively the press is closed with a two-step operation and upon the operation of the second piston the press is closed with a one-step operation.

7. In a pressing machine, cooperating pressing elements one of which is movable toward and from the other, motor means for actuating the movable element with a two step closing movement first into a position adjacent the other element and second into final pressing coaction therewith, an operator-operated member for controlling the first actuating step of the motor means, a second operator-operated means for controlling the second actuating step of the motor means and operable independently of the first control member, means operable at will for locking the first control member in its operated position, operator-operated releasable means operable automatically to lock the second control member in its operated position, and means to release the locking means.

8. In a pressing machine, cooperating pressing elements one of which is movable toward and from the other, motor means for actuating the movable element with a two step closing movement first into a position adjacent the other element and second into final pressing coaction therewith, an operator-operated member for controlling the first actuating step of the motor means, a second operator-operated means for controlling the second actuating step of the motor means operable independently of the first control member, and means operable at will for

locking the press closed in the first position before and after the second step.

9. In a pressing machine, cooperating pressing elements, one of which is movable toward and from the other, motor means for actuating the movable element with a two step closing movement first into a preliminary closed position and second into final pressure position, operator-

operated means for controlling the two step operation, operator releasable means for locking the press in final closed position and in preliminary closed position during the closing movement of the press and in the preliminary closed position 5 upon release of the motor means from delivery of heavy pressure.

ERNEST DAVIS.
